UNITED STATES PATENT OFFICE.

ALFRED P. HAUSTETTER, OF NORWOOD, OHIO, ASSIGNOR TO THE VICTOR SAFE & LOCK COMPANY, OF CINCINNATI, OHIO, A CORPORATION OF OHIO.

SAFE-LOCKING DEVICE.

1,132,089.

Specification of Letters Patent. Patented Mar. 16, 1915.

Application filed July 25, 1914. Serial No. 352,980.

To all whom it may concern:

Be it known that I, ALFRED P. HAUSTETTER, a citizen of the United States, residing at Norwood, in the county of Hamilton and State of Ohio, have invented certain new and useful Improvements in Safe-Locking Devices, of which the following is a specification.

My invention relates to improvements in devices for operating the locking and closing devices for the doors of vaults, safes and the like.

The object of my invention is to provide certain improvements in such devices which will make the same more convenient while at the same time presenting an effective arrangement in which it is impossible for the bolts to be thrown when the combination or combinations of the locking devices are not open, it also being impossible to manipulate the pressure device to cause pressure in the direction for opening the door to be exerted before the bolts have been thrown into inoperative position.

Other objects of my invention relating to the construction of my improved devices will appear more fully from the following specification.

In common practice, the combination lock operating devices in vault and safe doors are generally located to the right of the door and the bolt arbor to the left of the door, the pressure device, whereby the door is firmly pressed into its opening, being operated from the central portion of the door. In accordance with my invention, the bolts are operated from a central position, whereby the whole bolt operating mechanism is effectively balanced. The combination locking devices and also the eccentric pressure device referred to are operated by revoluble members which are concentric with each other and with the bolt arbor, the various hand-wheels or means for operating these parts being arranged in line with each other at the central portion of the door. With this arrangement in opening the door the graduated hand-wheel operating a combination lock is first operated, and if two combination locks are used, the hand-wheel for the second lock is next operated, after which the hand-wheel for throwing the bolts is rotated and after that the hand-wheel for operating the eccentric

pressure device for withdrawing the door from its opening is operated, these various operating hand-wheels being in line with each other and readily manipulated in proper sequence as stated. In closing the door, the operations referred to above are repeated in reverse order.

In order that a clearer understanding of my invention may be had, attention is hereby directed to the accompanying drawings forming part of this specification and illustrating certain preferred embodiments of my invention.

In the drawings, Figure 1 represents a horizontal cross-section through a vault or safe door taken on line 1—1 of Fig. 2, the door being provided with a pair of locks governing the operativeness of the bolts, and means for manipulating the same, Fig. 2 is a rear view of the door, Fig. 3 is a front view of the same, Fig. 4 is a partial section taken on line 4—4 of Fig. 3, Fig. 5 is a detail section taken on line 5—5 of Fig. 3, Fig. 6 is an enlarged section taken on line 6—6 of Fig. 2, Fig. 7 is a sectional detail on an enlarged scale illustrating a manner of constructing the bolt arbor and locking spindles illustrated in Fig. 1, Fig. 8 is a partial sectional view similar to Fig. 1 of a modification in which a single combination lock only is employed and Fig. 9 is a partial rear elevation of the same.

Referring to the drawings, the door 1 has extending therethrough the lock spindle 2 on the outer end of which the dial 4 is secured preferably by providing the spindle 2 with a squared end on which the dial 4 is mounted, the dial being secured to the spindle as by means of the flat headed screw 4'. The gear 5 is secured to the other or inner end of spindle 2 by any suitable means, the function of this gear being to operate one of the combination locks as will be described. Surrounding the locking spindle 2 is a hollow sleeve or lock spindle 3 carrying at its inner end a gear 6 adapted to operate a second combination lock. A small hand wheel 7 is secured to the outer end of hollow lock spindle 3 by any suitable means, preferably by threading the hub 8 of hand wheel 7 on the end of the hollow lock spindle 3 and securing the same thereto by means of the locking set screws 9. Surrounding the hollow lock spindle 3

in my preferred construction is the hollow bolt arbor 10 which carries on its inner end a spur gear 11, set into the frame of the door in front of the lock plate 12 which is secured to the door by suitable means such as the set screws 13. The gear 11 engages with racks for throwing the bolts, as will be more fully explained hereafter. The bolt arbor 10 is provided on its forward end 10 with a hand wheel 14, the hub of which is secured to the end of the bolt arbor 10 by suitable means such as the headless set screws 15.

Surrounding bolt arbor 10 in my preferred construction is the hollow sleeve 16 provided on its outer end with the pilot wheel 17 secured to the end of the sleeve 16 by suitable means such as the headless screws 18. Sleeve 16 has secured thereto a 20 miter gear 19 whereby the eccentric pressure device may be operated as will be explained.

A detail of the preferred arrangement of the locking spindles and bolt arbor is shown 25 in Fig. 7. As illustrated in Fig. 7 and Fig. 1, the spindle 2 is provided with a collar 20, and hollow spindle 3 is formed of two parts in alinement with each other and having enlarged portions 3' and 3² surrounding the 30 collar 20 and provided with engaging clutch-teeth as indicated. Correspondingly, the hollow arbor 10 is formed of two aligned portions having enlarged portions 10' and 10² surrounding the enlarged portions 3', 35 3² of spindle 3 and provided with engaging clutch-teeth. A nut 21 is mounted about bolt arbor 10, surrounding the collar 10² of the arbor to prevent endwise movement of the arbor and spindles.

40 As stated, the gears 5 and 6 serve to operate combination locks which govern the operativeness of the bolts of the door in the usual manner. Lock casings 22 and 23 are secured to lock plate 12, gearing within lock 45 case 22 being rotatable through intermediate gears, such as 24, 25 and 26 from gear 5, and gearing within case 23 being rotated from gear 6 by means of a chain of gears such as 27 and 28, the gears 24, 25, 26, 27 50 and 28 being protected by a plate 29 covering the same and secured to the door as shown. Dial 4 has graduations on its outer rim, as also has hand-wheel 7, so that the locks within cases 22 and 23 may be set to 55 desired combinations and operated by turning dial 4 and hand-wheel 7 to the proper numbers. Universal bar 30 is connected at 31 and 32 to lock bolts 33 and 34 extending into lock casings 22 and 23 and movable into 60 or out of the casings by the combination locking devices therein when properly set. The gear 11 on bolt arbor 10 operates the various bolts of the door, when permitted to do so by the previous actuation of the 65 locking devices, by any suitable connection.

In the construction illustrated, carrying-bar 35 is formed with a vertical rack 36 integral therewith, meshing with the right side of gear 11, referring to Fig. 2. Upper vertical bolts, not shown, are integral with or secured to the carrying-bar 35. Carrying-bar 37 has vertical rack 38 integral therewith, meshing with gear 11 on the left side thereof, the bottom vertical bolts of the door (not shown) being integral with or carried by bar 37. Bar 35 is provided with rack-teeth 39 and 40 on its right and left sides respectively, with which mesh gears 41 and 42 respectively, studded to the door, which gears mesh respectively with racks 43 and 44 integral or carried by the right and left carrying-bars 45 and 46, which carry the right and left horizontal bolts 47 and 48 respectively. Similarly carrying-bar 37 is provided with rack-teeth 49 and 50 on its right and left sides, with which mesh gears 51 and 52, studded to the door, which respectively mesh with racks 53 and 54, also secured to or integral with carrying-bars 45 and 46, carrying horizontal bolts 47 and 48. The bolts are all represented as shot in Fig. 2. Obviously the rotation of gear 11 results in the outward or inward movement of all the bolts together, when movement of the carrying-bars is permitted by the locking devices. The various bolts are slidably mounted in supporting bars secured to the door, those for the horizontal bolts being shown at 55, 56, and 57, 58. It should be understood that this construction is given as illustrative and that any suitable operative connection between the various bolts of the door may be used, the novelty of the device, so far as the operation of the bolts is concerned, residing in the centrally-located bolt arbor 10 carrying gear 11 operating the bolts, whereby a direct or central drive for the bolts is provided, and the complete bolt-operating device is balanced.

70 The movement of bar 30 in accordance with the operation of the combination locks, referred to above, serves to operate a locking lever or equivalent device into or out of position to prevent or permit sliding movement of the bolts. In the construction illustrated, a bell-crank lever 59 is pivotally connected to bar 30 by a link 60 and is pivoted to the door at 61. The bell-crank has a horizontally extending arm 62, which constitutes the lock-lever referred to, the outer end of arm 62 extending through an opening in support or inner bolt bar 55, the end of arm 62 extending into a hole in a sliding plate 63, which is mounted to slide on supporting plate 64, having an L section on both sides of plate 63, and secured to inner bolt bar 55. Slide-plate 63 has an opening therein through which the extension 65 of sliding-plate 66, secured to carrying bolt plate 45, is adapted to pass when the locks have been 75 80 85 90 95 100 105 110 115 120 125 130

operated to permit the movement of lock-bolts 33 and 34 and the movement of slide-plate 63 to place the opening in plate 63 in line with member 65. Thus it is necessary 5 to operate lock-spindles 2 and 3 to operate bar 30 and bell-crank 59 to place plate 63 in unlocking position before the bolts can be retracted. The double locking device is arranged as is well known, so that both locks 10 must be operated to open the door, or may be arranged so that one lock will open the door, by shifting link 60 to the other stud shown at 67, and if lever 59 should be blown off the door, plate 63 will drop into position 15 to make it impossible to open the door, in the well-known manner.

The eccentric pressure device is operated as stated by the rotation of sleeve 16 carrying miter gear 19. The latter engages with 20 miter gears 68 and 69 mounted on vertical shafts 70 and 71, the gears preferably being mounted in a gear box 72 through which shafts 70 and 71 extend. In the form of my invention illustrated, pressure is applied 25 to the door at four points to seat the same in its opening as closely as possible when the door is to be locked, the pressure devices also serving to open the door. In the construction illustrated, shafts 70 and 71 are 30 connected by worm-gears with horizontal shafts 73 and 74 mounted in bearings 75 and provided with the usual eccentric pins 76 mounted in suitable curved tracks 77 secured to the wall surrounding the door opening so 35 that actuation of pilot-wheel 17 will result in the application of pressure at the four corners of the door to seat the door closely in its opening or to move the door from its opening, the door being hung from the wall 40 in the manner usual with safe or vault doors of this character.

In Figs. 8 and 9, I have illustrated a modification in which a single lock and accordingly a single lock-spindle are employed. As there illustrated, the lock-spindle 2 having collar 20 formed thereon and carrying gear 5 on its inner end is surrounded by the bolt arbor 10 carrying gear 11, the second lock-spindle 3 and connected parts described in connection with Figs. 1 and 2 being omitted. Bolt arbor 10 is formed of two parts which may be joined together by clutch-teeth as described in connection with Fig. 1, or which may be formed 55 as illustrated in Fig. 8 by screwing the two alined parts of arbor 10 together and locking the same with a suitable set-screw, nut 21 being used to prevent endwise movement of the spindle and arbor as described 60 in connection with Fig. 1. In this construction, since only a single combination lock in case 22 is used, the bar 30 described in connection with the first form of my device is not necessary, locking-lever 62 in this case 65 forming one arm of a bell-crank, the other

arm of which is pivoted to the lock bolt 33 slidably into and out of lock-case 22.

In both forms described of my invention, it will be obvious that a well balanced efficient and convenient form of mechanism is 70 provided in which the various hand-operating mechanisms are located in line with each other at the central part of the door in position to be readily operated in proper sequence as has been described. 75

Having now described my invention, what I claim as new therein and desire to secure by Letters Patent is as follows:—

1. In a safe door locking device, the combination of a door, a plurality of revoluble 80 members concentrically mounted extending through the same, means on the outer ends of said members for independently rotating the same, bolts mounted on the inner side of said door, locking devices for preventing or 85 permitting operation of said bolts, pressure means for seating and unseating said door, and connections between said bolts, locking devices and pressure means respectively and different ones of said members for operating 90 the same by the rotation of said members respectively, substantially as set forth.

2. In a safe door locking device, the combination of a door, bolt plates carrying outwardly extending bolts slidably mounted on 95 the door, a bolt arbor extending centrally through the door, a gear carried thereby, racks meshing with said gear and secured to two of said bolt plates, and operative connections from said bolt plates to the remaining 100 bolt plates, substantially as set forth.

3. In a safe door locking device, the combination of a door, a plurality of concentrically mounted revoluble elements extending centrally through the same, means on the 105 outer ends of said elements for independently rotating the same, locking means mounted on said door, pressure means for controlling the seating of said door and connections between said locking means and 110 pressure means respectively and different ones of said elements for operating the same by the rotation of said elements respectively and sequentially, substantially as set forth.

4. In a safe door locking device, the combination of a door, a plurality of concentrically mounted revoluble elements extending centrally through the same, means on the outer ends of said elements for independently rotating the same, bolts mounted on said door, 115 locking devices for preventing or permitting operation of said bolts, pressure means for seating said door or forcing the same away from the door opening, and connections between said bolts, locking devices 120 and pressure means respectively and different ones of said elements for operating the same by the rotation of said elements respectively and sequentially, substantially as 125 set forth. 130

5. In a safe door locking device, the combination of a door, bolt plates carrying outwardly extending bolts slidably mounted on the same, a bolt arbor extending centrally
5 through the door, a lock spindle mounted concentrically therewith; a gear carried by said bolt arbor, racks meshing with said gear and secured to two of said bolt plates, operative connections from said bolt plates
10 to the remaining bolt plates, locking devices

arranged to prevent or permit movement of one of said bolt plates, and operative connections between said lock spindle and locking devices, substantially as set forth.

This specification signed and witnessed 15
this 21st day of July, 1914.

ALFRED P. HAUSTETTER.
